CLAIM

The ornamental design for a set of modules for a modular mount for circuit boards, as shown and described.

DESCRIPTION

FIG. 1 is a perspective view from above, of an intermediate module of the set of modules for modular mount for circuit boards showing my design;

FIG. 2 is a perspective view from below, of the modular mount of FIG. 1;

FIG. 3 is a top plan view thereof;

FIG. 4 is a bottom plan view thereof;

FIG. 5 is an end view from one end thereof, the other end being a mirror image thereof;

FIG. 6 is a side elevational view one side thereof, the other side being a mirror image thereof;

FIG. 7 is a perspective view of an end module of the set of modules for modular mount for circuit boards of FIG. 1 as viewed from its outer face;

FIG. 8 is a perspective view of the end module of FIG. 7, as viewed from its inner face;

FIG. 9 is a bottom plan view of the end module of FIG. 7;

FIG. 10 is an end view of the end module of FIG. 7 from its inner face;

FIG. 11 is an end elevational view of the top module of FIG. 7 from its outer face;

FIG. 12 is a side elevational view of the end module of FIG. 7; and,

FIG. 13 is a side elevational view of the end module of FIG. 7 from its outer face.
